Primary Examiner — Cynthia Ramirez

(74) Attorney, Agent, or Firm — Hanrahan Law Firm,
P.A.; Benjamin M. Hanrahan(57) **CLAIM**The ornamental design for a composting bag assembly, as
shown and described.

DESCRIPTION

FIG. 1 is a perspective view for a composting bag assembly,
showing my new design.

FIG. 2 is another perspective view thereof.

FIG. 3 is a front view thereof.

FIG. 4 is a left side view thereof.

FIG. 5 is a rear view thereof.

FIG. 6 is a right side view thereof.

FIG. 7 is a front view thereof with a bottom cap section
removed and with the bag cinched.FIG. 8 is a front, exploded view thereof with the bottom cap
removed and with the bag open.

FIG. 9 is a top view thereof; and,

FIG. 10 is a bottom view thereof.

The broken lines in the figures illustrate portions of the
composting bag assembly which form no part of the claimed
design. Additional broken lines show environment and form
no part of the claimed design.**1 Claim, 10 Drawing Sheets**(56)
